UNITED STATES PATENT OFFICE

139,002

DESIGN FOR A BEVERAGE DISPENSER OR THE LIKE

Charles Pokol, Hollywood, Calif.

Application June 26, 1944, Serial No. 114,197

Term of patent 7 years

(Cl. D2—3)

To all whom it may concern:

Be it known that I, Charles Pokol, a citizen of the United States residing at Hollywood, in the county of Los Angeles and State of California, have invented a new, original, and ornamental Design for a Beverage Dispenser or the Like, of which the following is a specification, reference being had to the accompanying drawing, forming a part thereof.

In the drawing:

I claim:

The ornamental design for a beverage dispenser or the like, substantially as shown and described.

CHARLES POKOL.
